UNITED STATES PATENT OFFICE.

WARREN V. DEVEREUX, OF AURORA, ILLINOIS, ASSIGNOR TO RICHARDS-WILCOX
MANUFACTURING COMPANY, OF AURORA, ILLINOIS, A CORPORATION OF
ILLINOIS.

FUSIBLE LINK.

1,192,396.

Specification of Letters Patent. Patented July 25, 1916.

Application filed November 15, 1915. Serial No. 61,524.

To all whom it may concern:

Be it known that I, WARREN V. DEVEREUX, a citizen of the United States, and a resident of Aurora, in the county of Kane, State of Illinois, have invented certain new and useful Improvements in Fusible Links, of which the following is a specification, reference being had to the accompanying drawing.

This invention relates to improvements in fusible links primarily adapted for use, in connection with chains or other flexible connections, for retaining doors, windows, skylights, &c., in opened position, but which may be relied upon to permit the closing of the door or other device when the link is subjected to a predetermined temperature.

The leading objects of the invention are to provide a device comprising two similar members that can be very readily and cheaply manufactured and that can be united by a comparatively small amount of solder or other fusible material, with such solder or fusible material so applied as to be quickly affected by heat; to construct each of the members of the link from a single thin sheet of metal having a flange to so stiffen it that it will not be easily bent or distorted; and to provide each of the members with means for engagement by the other member of such a character as to impose no great strain on the fusible material that unites them, but which will, upon the weakening or destruction of the fusible material by heat, permit an instantaneous separation of such members.

It is a further object to produce a construction that will permit the members to be again united and used, if desired, after the device has been once used and the original fusible material melted.

These objects I accomplish by the construction and arrangement of parts as shown in the drawing and hereinafter specifically described.

In the drawings: Figure 1 is a side elevation of the link; Fig. 2 is a top or plan view of the same; Fig. 3 is a longitudinal section taken at line 3—3 of Fig. 2; Fig. 4 is a view, in side elevation, of the two members of the device before they are united; Fig. 5 is a cross-section taken at line 5—5 of Fig. 1; and Fig. 6 is a perspective view of one of the members of the link.

In all of the views the device is shown considerably enlarged in order to better illustrate the construction.

Referring to the several figures of the drawing, A, A, indicate the two members of the link, such members, in the construction shown, being formed exactly alike. Each of such members is formed from a comparatively thin piece of sheet-metal and is preferably enlarged at one end and there made semi-circular in shape, as best shown in Fig. 2. In such enlarged end is formed a hole *a* in which is secured a suitable eyelet *b*.

c indicates a flange extending around the eyeleted end referred to and extending along the parallel side edges to the opposite end of the member. At such opposite end the metal is bent or turned to form a lip *d* that extends across from side to side of the member. About midway of its length, in the form of construction shown, each member A is bent to form a transversely-extending shoulder *e*, against which, when the parts are secured together, the lip *d* of the other member rests. Each of these lips *d* and shoulders *e* is slightly inclined so that when the fusible material that holds the two members A, A, together is destroyed or weakened the two members will not be liable to be held interlocked but will readily separate.

f indicates the solder or other fusible material for uniting the two members.

In arranging the two members A, A, in proper relation to each other so that when joined they will form a complete device, they are to be placed back to back, or so that their respective flanges *c* extend in opposite directions, as is clearly shown in Fig. 5. The inclined end lip *d* of each member is to engage the correspondingly-inclined shoulder *e* of the other member, and when the two members are so placed with relation to each other the solder, or other fusible material, *f*, is to be applied to the outer sides of the flanges *c* from opposite the end lips *d* to opposite the shoulders *e*—in other words, to those portions of the flanges on the overlapping parts of the two members A. If desired, fusible material may also be applied transversely over each joint formed by a lip and shoulder, as indicated in Figs. 1 and 2 at *g*.

Flanging the members as shown and described not only provides a very stiff construction for each member, even if made from quite thin sheet-metal, but it also enables a comparatively wide surface to be

provided for the application and retention of the solder or other fusible material when the two members A, A, are overlapped back to back or so that the flanges extend in opposite directions. Furthermore, in this construction the fusible material is so situated as to be particularly susceptible to attack by flame or highly heated air, and hence will weaken or melt more readily than when it is in the form of a plug or other solid uniting device passing through the separable members of the link. With the fusible material weakened or melted it will be understood that oppositely-directed strains applied at the ends of the members A, A, through chains or like flexible connections fastened thereto, will cause an immediate separation of the two parts of the link, inasmuch as the inclination of the engaging lips and shoulders offers no obstruction whatever to such separation. When the two members are united, as described, however, the engagement between the lips and shoulders is such as to, in a very large measure at least, relieve the fusible material itself from the separating strain to which the link as a whole is subjected to in use.

What I claim as my invention and desire to secure by Letters Patent is—

- 30 1. A fusible link comprising, in combina-

tion, two members arranged in overlapping relation, the opposed faces of said overlapping members abutting and being in intimate contact with each other, side flanges on each member projecting in opposite directions, a transverse shoulder intermediate the ends of each member, and a lip at one end of each of said members, the lip of each member engaging the shoulder of the other member, a fusible material applied over the outer faces of the flanges of the overlapping portions of the two said members.

2. A fusible link comprising, in combination, two members arranged in overlapping relation, the opposed faces of said overlapping members abutting and being in direct contact with each other, each of said members having an inclined lip at one end and an inclined transverse shoulder intermediate its ends, the lip of each member engaging the shoulder of the other, side flanges on the overlapping portion of each member, the flanges of one member projecting in a direction opposite to those on the other member, and a fusible material applied to the outer faces of said flanges and over the joint formed by said lip and shoulder for connecting the flanges together.

WARREN V. DEVEREUX.
